UNITED STATES PATENT OFFICE.

JOHN SORENSEN, OF BROOKLYN, NEW YORK.

AUTOMATIC FEED APPARATUS FOR EVAPORATOR-SHELLS.

1,166,273.

Specification of Letters Patent. Patented Dec. 28, 1915.

Application filed March 31, 1915. Serial No. 18,857.

To all whom it may concern:

Be it known that I, JOHN SORENSEN, a citizen of the United States, residing at Brooklyn, in the county of Kings and State of New York, have invented certain new and useful Improvements in Automatic Feed Apparatus for Evaporator-Shells, of which the following is a specification.

My invention relates to automatically operating apparatus for feeding a liquid to an evaporator or evaporator shell, operating under vacuum.

An important object of the invention is to provide apparatus of the above mentioned character, which operates wholly automatically and is reliable in such operation.

A further object of the invention is to provide apparatus of the above mentioned character which is simple in construction, inexpensive to manufacture, strong, and durable.

A further object of the invention is to provide apparatus of the above mentioned character, having parts which are adjustable so that the level of the liquid in the evaporator shell may be varied, at will, and maintained at the new level.

Other objects and advantages of the invention will be apparent during the course 30 of the following description.

In the accompanying drawings, forming a part of this specification, the figure is a central vertical sectional view through apparatus embodying my invention, parts 35 thereof being shown in elevation.

In the drawing, wherein for the purpose of illustration is shown a preferred embodiment of my invention, the numeral 1 designates an evaporator casing or shell, operating 40 under suitable vacuum which is maintained therein by a vacuum pump, not shown. This evaporator shell is heated by any suitable means, also not shown.

The numeral 2 designates a liquid feed 45 pipe, which leads into the evaporator shell at a point suitably spaced from its bottom. The feed pipe 2 has a valve casing 3 connected thereto. This valve casing has a passage 4 and a movable or pivoted valve 5 controls 50 the flow of liquid therethrough. The valve 5 is rigidly mounted upon a transverse rod 6, extending to the exterior of the valve casing 3 and rigidly connected with a lever or crank 7, having a weight 8 connected with 55 its outer end, serving to normally hold the

valve 5 closed. The feed pipe 2 has communication with a feed tank 9, as shown.

Communicating with the evaporator shell 1 is a vertical float shell or chamber 10, having a liquid level identical with the liquid 60 level in the evaporator shell 1, as shown. Connected with the upper end of the float shell or chamber 10 is a pipe section 11, having connection with a T-coupling 12. A horizontal vacuum pipe 13 is connected with 65 the coupling 12 and is connected by an elbow 14, with a pipe 15, which leads into the upper end of the evaporator shell 1, as shown. Connected with the coupling 12 is a pipe-extension 16, carrying a removable 70 cap 17, having screw-threaded engagement therewith.

Extending longitudinally within the vacuum pipe 13 is an approximately horizontal vertically swinging lever 18, pivoted at 19, 75 with the pipe. At its free end this lever is provided with a transverse opening 20, for the passage of a vertical rod 21, having spaced openings 22, receiving a transverse pin 23. It is thus apparent that the rod 80 20 is carried by the free end of the lever and may be vertically adjusted with relation thereto. Access is had to the rod 21 for vertically adjusting it with relation to the lever 18, by removing the cap 17. Connected with 85 the lower end of the rod 21 is a flexible element, such as a chain 24, the lower end of which is attached to a float 25, engaging the liquid within the float shell or chamber 10, as shown. The float 25 controls the upward 90 and downward movements of the lever 18 and when the level of the liquid in the shell 10 rises, the lever 18 is swung upwardly by a suitably stiff retractile coil spring 26, attached thereto, as shown at 27. The pipe 13 95 is provided with a nipple 28, having engagement with a vertical shell or housing 29, the upper end of which is closed by a cap 30 or the like. A longitudinally adjustable bolt 31 has screw-threaded engagement with 100 this cap and its inner end is attached to the spring 26, while its outer end projects exteriorly of the cap so that the bolt may be readily turned. A removable protecting cap 32 surrounds the upper end of the bolt 31 105 and has screw-threaded engagement with a tubular extension 33 of the cap 30. It is thus apparent that means are provided to regulate the tension of the spring 26.

The pipe 13 is further provided with a 110

nipple 34, having connection with a vertical shell 35. At its upper end the shell 35 is provided with an air inlet valve seat 36, adapted to be engaged and disengaged by a downwardly seating air inlet valve 37, rigidly mounted upon a vertical reciprocatory rod 38. An upwardly seating suction or vacuum valve 39 is rigidly mounted upon the lower portion of the rod 38 and is adapted to engage a valve seat 40 arranged in the upper end of the nipple 34. It is apparent that when the valve 37 is closed the valve 39 is open and vice versa. The rod 38 is pivotally connected, as shown at 41, with the lever 18.

The numeral 42 designates a vacuum cylinder, one end of which is connected with a pipe 43, communicating with the interior of the shell 35. This cylinder is preferably vertically arranged and supported by any suitable means and has a plunger 44 or vacuum operated member connected therein. The end of the cylinder 42 beneath the plunger 44 is preferably apertured and a depending rod 45 is connected with the plunger 44. A flexible element, such as a chain 46 or the like, is attached to the rod 45 and extends downwardly for connection with the free end of the lever 7.

The numeral 47 designates a vacuum whistle, connected with a coupling 49, preferably having screw-threaded engagement with the outer end of the shell 35 and also serving as a housing for the valve 37. Upon the valve 39 being slightly opened and before the valve 37 has time to close, air will be drawn in through the whistle 47 and the whistle sounded, thus enabling the operator to ascertain each time the valves are shifted.

The operation of the apparatus is as follows: When the level of the liquid in the evaporator shell 1 falls below a predetermined degree, the float 25 descends, which swings the end of the lever 18 downwardly. This movement of the lever draws the rod 38 downwardly, opening the vacuum valve 39 and closing the air inlet valve 37. The vacuum pipe 13 is in free communication with the interior of the evaporator shell 1 through the pipe 15 and hence the same degree of vacuum is maintained therein. When the valve 39 opens with the valve 37 closed, a vacuum is created in the shell 35 and in turn in the cylinder 42. The plunger 44 is then moved upwardly by atmospheric pressure. This upward movement of the plunger 44 moves the chain 46 upwardly, which in turn swings the lever 7 upwardly and opens the valve 5. The liquid is now drawn through the pipe 2 into the evaporator shell, which continues until the predetermined level of the liquid in the shell 1 is restored, at which time the float 25 is elevated and the lever 18 swung upwardly by the spring 26. Upon the upward movement

of the lever the vacuum valve 39 is closed and the air inlet valve 37 opened, the cylinder 42 being then placed in communication with the atmosphere. The plunger 44 is then free to drop, and the weight 8 will return the valve 5 to the closed position.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described the invention, I claim:

1. In an automatic feeding apparatus, the combination with a vacuum evaporator shell, of a float chamber communicating with the lower portion thereof, a vacuum conduit connected with the evaporator shell and with the float chamber, a pivoted lever arranged within the conduit, a float operating within the float chamber, means connecting the float and the lever, a vacuum cylinder connected with the vacuum conduit, a valve controlling communication between the vacuum cylinder and conduit and connected with the lever to be operated thereby, a liquid feed conduit communicating with the evaporator shell, a valve connected with the feed conduit to control the passage of liquid therethrough, a plunger operating within the vacuum cylinder, and means connecting the plunger with the valve which is connected with the feed plunger.

2. In an automatic feeding apparatus, the combination with a vacuum evaporator shell, of a float chamber communicating with the shell below the liquid level thereof, a conduit connecting the shell and chamber above the liquid levels thereof, a float arranged within the float chamber, a movable lever connected with the float, pressure operated means connected with the conduit, a valve for controlling communication between the pressure operated means and the conduit and connected with the movable lever to be operated thereby, a feed conduit leading into the evaporator shell, a valve connected with the feed conduit, and means connecting the feed conduit valve and the pressure operated means.

3. In an automatic feeding apparatus, the combination with a vacuum evaporator shell, of a float chamber communicating with the shell below the level of the liquid therein, a conduit connecting the shell and chamber above the liquid levels thereof, a float arranged within the float chamber, a movable member connected with the float, pressure operated means connected with the conduit, a valve for controlling the communication between the pressure operated means and the conduit and connected with

- the movable member to be operated thereby, and liquid feed means connected with the evaporator shell and operated by the pressure operated means.
5. 4. In an automatic feeding apparatus, the combination with a vacuum evaporator shell, of a float chamber communicating with the shell below the liquid level thereof, a vacuum conduit connected with the shell above the level of the liquid therein, a float arranged within the float chamber, a movable member connected with the float; pressure operated means connected with the vacuum conduit, means operated by the movable member for controlling the communication between the pressure operated means and the vacuum conduit, and liquid feed means connected with the evaporator shell and operated by the pressure operated means.
5. In an automatic feeding apparatus, the combination with a vacuum evaporator shell, of a vacuum conduit connected therewith above the liquid level therein, a float operated by the rise and fall of the liquid level in the vacuum evaporator shell, pressure operated means connected with the vacuum conduit, means operated upon the movement of the float to control the communication between the vacuum conduit 30 and the pressure operated means, and liquid feed means discharging into the evaporator shell and connected with the pressure operated means.
6. In an automatic feeding apparatus, the combination with a vacuum evaporator shell, of a vacuum conduit connected therewith above the liquid level therein, a vacuum cylinder, a valve structure connected with the vacuum cylinder and embodying 40 a plurality of valves to alternately establish communication between the vacuum cylinder and the vacuum conduit and the vacuum cylinder and the atmosphere, means operated by the rise and fall of the liquid 45 level in the evaporator shell to shift the valves, a movable member arranged within the vacuum cylinder, and liquid feed means discharging into the evaporator shell and connected with the movable member to be 50 operated thereby.

In testimony whereof I affix my signature in presence of two witnesses.

JOHN SORENSEN.
